CLAIM

The ornamental design for a top guide for a window balance, as shown and described.

DESCRIPTION

FIG. 1 is a perspective view of a top guide for a window balance, as incorporated into a window balance, showing my new design.

FIG. 2 is a perspective view of the top guide for a window balance of FIG. 1.

FIG. 3 is a front elevation view of the top guide for a window balance of FIG. 1.

FIG. 4 is a back elevation view of the top guide for a window balance of FIG. 1.

FIG. 5 is a right elevation view of the top guide for a window balance of FIG. 1.

FIG. 6 is a left elevation view of the top guide for a window balance of FIG. 1.

FIG. 7 is a top plan view of the top guide for window a balance of FIG. 1; and,

FIG. 8 is a bottom plan view of the top guide for a window balance of FIG. 1.

The broken lines depict environmental portions of the top guide for a window balance and form no part of the claimed design.

1 Claim, 7 Drawing Sheets
